UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A LADY'S POLONAISE.

SPECIFICATION forming part of Design No. 14,559, dated January 22, 1884.

Application filed November 19, 1883. Term of patent 3½ years.

To all whom it may concern:

Be it known that I, CATHERINE O'HARA, of the city, county, and State of New York, have invented and produced a new and original Design for a Pattern of a Lady's Polonaise, (numbered 8,982;) and I do hereby declare that the engraved prints accompanying this specification convey to any one accustomed to using paper patterns a clear understanding of how a garment made up by the pattern will appear.

The design shows close-fitting fronts buttoned from the neck to a little below the waistline, the left front being undraped at its front edge, slightly draped by plaits at its back edge, and crossed from the closing to the hip by the

right front, which is draped high by plaits at the overlapping edge, and also at its back edge, a close-fitting back exhibiting loopings at its side edges, and underfolded plaits at the ends of its three seams, close-fitting coat-sleeves, and a standing collar.

What I claim as my invention, and desire to secure by Letters Patent, is—

The design for a lady's polonaise, as shown in the engraved prints accompanying this specification.

CATHERINE O'HARA.
